Term of patent 7 years

(Cl. D56—4)

FIG. 1.

Des. 194,763

PAGE 2

FIG. 2

FIG. 3

FIGURE 1 is a front perspective view of a television receiver showing my new design;

FIGURE 2 is a front perspective view of another embodiment of a television receiver showing my new design and which embodiment differs from that of FIGURE 1 primarily by the addition of a bezel overlying forward and peripheral edge portions of the tube face; and

FIGURE 3 is a rear perspective view of the television receivers shown in FIGURES 1 and 2.

The sides of the television receiver opposite those shown in FIGURES 1, 2 and 3 are substantially the same in appearance as the respective sides shown except for the omission of the control knobs.

Dominant features of the design shown in full lines.

This application is a continuation-in-part of my earlier application Serial No. D-59,210 filed February 1, 1960 and now abandoned.

I claim:

The ornamental design for a television receiver, as shown and described.
